UNITED STATES PATENT OFFICE.

HARRY HERBERT, OF CHROME, NEW JERSEY, ASSIGNOR OF ONE-HALF TO BENJAMIN LEBOVITZ, OF CHROME, NEW JERSEY.

OIL-CAN CLOSURE.

1,266,463.

Specification of Letters Patent. Patented May 14, 1918.

Application filed February 9, 1917. Serial No. 147,650.

To all whom it may concern:

Be it known that I, HARRY HERBERT, a citizen of the United States, residing at Chrome, in the county of Middlesex and 5 State of New Jersey, have invented new and useful Improvements in Oil-Can Closures, of which the following is a specification.

This invention relates to oil cans.

The primary object of the invention is to

10 provide a can in which the inlet and outlet opening will be normally closed in order to prevent the escape of vapor, such as is usually given off by gasoline or other volatile liquids, the escape of this vapor reducing 15 the quality of the liquid, besides being of a highly inflammable and dangerous character.

Another object is to provide a can in which the inlet and outlet openings are normally automatically closed, but when it is desired to remove the contents of the can, said opening will be automatically opened by the canted position of the can in which it is usually held during the pouring operation, 25 the opening of the inlet permitting the passage of air therethrough into the interior of the can to aid in the pouring operation, as will be readily understood.

With the above and other objects in view 30 the invention consists of the following novel combination and arrangement of parts, hereinafter more fully described and illustrated in the accompanying drawings, in which—

Figure 1 is a side elevation of an oil can 35 constructed in accordance with the present invention and illustrating the bail of the can in the position it assumes when the inlet and outlet openings are closed.

Fig. 2 is a similar view, showing the can 40 tilted or canted and illustrating the bail in the position it assumes when the inlet and outlet openings are opened, to permit emptying the can.

Fig. 3 is a top plan view of the can in the 45 position shown in Fig. 1.

Fig. 4 is a vertical sectional view through the upper part of the can and illustrating the valves of the inlet and outlet openings in their closed position, the cam loop for actuating these valves being shown by dotted lines.

Fig. 5 is a similar view showing the can in a tilted position and illustrating the valves opened.

Fig. 6 is a perspective view of the bail and 55 its integrally formed cam loops shown detached from the can, and

Fig. 7 is a similar view of the inlet valve and its associated stem and cross arm.

Fig. 8 is a sectional view illustrating a modified form of the invention and Fig. 9 is a fragmentary section taken at right angles to Fig. 8.

In the practical embodiment of the invention, there is illustrated a can of the 65 usual or any preferred construction, such can being designated at 10. This can is provided with the usual inlet or filling opening 11 and the usual outlet or spout 12. The inlet opening 11 is provided with an up- 70 standing surrounding flange 13, the said flange being formed at its juncture with the can top 14 with an annular valve seat 15, while the inlet spout 12 is formed at its juncture with the top 14 with a valve seat 75 16, both of these valve seats being of tapered form. Secured beneath the inlet opening 11 is a U shaped guiding yoke 17, the said yoke being provided with an opening 18 through which is adapted to operate 80 a vertically movable valve stem 19, which carries a valve 20. This valve is shaped to conform to the valve seat 15 and is normally held against the seat by means of a spring 21, which surrounds the stem 19 and is interposed between the yoke 17 and a collar 85 22 fast to the stem 19.

Secured across the inlet 11 upon the opposite side of the valve 20 is a cross bar 23, for the purpose of providing a further guiding 90 means for the stem 19, the said cross bar being formed with an opening therethrough for the passage of the stem.

Secured beneath the inlet opening 12 is a yoke 24, similar in formation to the yoke 95 17 previously described, this yoke is formed with an opening 25 for the passage of a valve stem 26, which carries the valve 27, which, is adapted to fit and normally close the valve seat 16. The yoke 24 is provided 100 with a cross bar 28, which has an opening therethrough to provide additional guiding means for the stem 26. The valve 27 is normally held in its closed position through the medium of the spring 29 which surrounds a valve stem, this spring being interposed 105 between a yoke 24 and a collar 30 secured to said stem. The stems 19 and 26 are con-

nected by means of links 31, the said links being pivoted at 32 and 33 respectively to each of the said stems.

The valve stem 19 carries at its upper 5 end a cross arm 34, this cross arm passing through and working in guide slots 35 formed at diametrically opposite points in the flange 13. The outer ends of the cross arm are adapted to pass through and engage arcuate cam loops 36, which are formed on the inner ends of the bail 37. This bail is formed with substantially horizontal portions 38, by means of which it is pivoted to the top of the can as shown at 39 10 and is also provided with a hand grip 40 for the convenience of handling.

It will be seen from the above description and the accompanying drawings, that when the bail and can are in vertical positions 20 that both of the valves 20 and 27 will remain upon their respective seats and close the openings 11 and 12. When it is desired to move the contents from the can, the said can is lifted by means of the bail 37 and 25 is tilted or canted by grasping the rear of the bottom edge in the usual manner. This action causes the cam loops 36 to engage the ends of the cross arm 34 and press the said arm inward, carrying with it the valve stem 30 and forcing the valve 20 open against the action of the spring 21. This operation through the connecting link 34 pulls inward the stem 26 and the valve 27, opening the outlet 12. The simultaneous opening of 35 these valves permits the contents of the can to be poured through the outlet 12 and at the same time permits the entrance of air into the can through the inlet opening 11 to more readily aid in the removal of the 40 contents. As soon as the can is relieved from its tilted position and the bail 37 allowed to resume its normal position the valves 20 and 27 will be automatically closed by the action of the springs 21 and 29 respectively. When it is desired to fill the can it 45 is only necessary to rock the bail 37 upon its pivots, which opens the valves and permits entrance to the can.

In Fig. 8 there is illustrated a modification 50 of the invention, showing the method of controlling the valves 20' and 27' by means of a single spring. In this construction the stems 19' and 26' are shown as formed from a single piece of wire, the 55 spring 21' surrounding the stem 19' and being interposed between the collar 22' and the yoke 17', this yoke serving as a guiding means in both of the valve stems. In this

construction the opening 35 in the flange 13 is eliminated to avoid the possibility of 60 liquid passing out through these openings when the can is being filled. In order to operate the valves, the cam loops 36 which are carried by the bail 37 receive the opposite ends of a cross bar 50, which is connected to the stem 19' and is formed in the arches 51, which straddle the flange 13 so that the opposite ends thereof may engage these loops.

The operation of the device is the same 70 as the construction previously described.

Having described the invention, what I claim is:

1. An oil can comprising a receptacle provided with an inlet and an outlet opening, 75 valves for each of said openings, a bail pivoted to said receptacle and means including cam loops carried by said bail for automatically opening both of said valves upon tilting the can.

2. An oil can comprising a receptacle provided with inlet and outlet openings, valves for each of said openings, a cross arm carried by one of said valves, a bail pivoted to said receptacle and means operated by 85 said bail and engaging said cross arm for controlling said valves.

3. An oil can comprising a receptacle provided with inlet and outlet openings, valves for each of said openings, a cross arm carried by one of said valves, a bail pivoted to said receptacle and cam loops carried by said bail and engaging said cross arm for controlling said valves.

4. An oil can comprising a receptacle provided with inlet and outlet openings, valves for each of said openings, a cross arm carried by one of said valves, a bail pivoted to said receptacle and cam loops formed on the inner ends of said bail and engaging 100 said cross arm for controlling the operation of both of said valves.

5. An oil can comprising a receptacle provided with an inlet and an outlet opening, valves for each of said openings, a pivoted 105 link connecting said valves, a cross arm carried by one of said valves, a bail pivoted to said receptacle and cam loops formed on the inner ends of said bail and engaging said cross arm, whereby, the tilting of said 110 can with respect to the bail will cause the automatic opening of both of said valves through the pivoted link connection.

In testimony whereof I, affix my signature.

HARRY HERBERT.
